UNITED STATES PATENT OFFICE

ANDREW B. CLARK, OF THOMASVILLE, GEORGIA, ASSIGNOR OF ONE-HALF TO ROSCOE LUKE, OF THOMASVILLE, GEORGIA

DOORCHECK

Application filed May 27, 1929. Serial No. 366,416.

This invention aims to provide a novel means for checking the closing movement of a door, and to provide novel means for bringing about a closing of a door.

It is within the province of the disclosure to improve generally and to enhance the utility of devices of that type to which the invention appertains.

A preferred form of the invention has been shown in the drawings, but it will be understood that a mechanic, working within the scope of what is claimed, may make such changes as his skill may suggest, without departing from the spirit of the invention.

In the accompanying drawings:

Figure 1 shows in elevation, a device constructed in accordance with the invention, mounted on a door;

Figure 2 is a top plan, wherein the door and the door jamb are shown in section;

Figure 3 is a longitudinal section of the device, some parts remaining in elevation;

Figure 4 is a fragmental sectional view showing parts as they will appear whilst the door is being opened, the clutch being disengaged from the nut, the shaft sliding freely, and the nut rotating with the shaft;

Figure 5 is a view similar to Figure 4, the parts being in the positions which they will assume whilst the door is being closed, the clutch being engaged with the nut, and rotation being imparted to the screw rod;

Figure 6 is a cross-section on the line 6—6 of Figure 5;

Figure 7 is a perspective view of the clutch;

Figure 8 is a perspective view of the nut;

Figure 9 is a perspective view of the inner sleeve.

The numeral 1 marks a door frame and a door 2 is hinged at 3 to the door frame 1.

A trough-shaped bracket 4 is secured to the door frame 1. In the side walls of the bracket 4 is journaled a ball 5 on one end of a screw rod 6.

The screw rod 6 carries a brake drum 7. The brake drum 7 is adapted to be engaged by a trough-shaped foot 8 on one end of a resilient brake arm 9, the arm 9 being reversely curved intermediate its ends, as shown at 10, to enhance its resiliency. The

inner end of the arm 9 is secured at 11 to the bracket 4. A screw 12 is threaded into the bracket 4 and engages the arm 9. The screw 12 forms a means whereby the pressure with which the foot 8 bears against the drum 7 may be adjusted.

The numeral 14 designates a tubular holder on one end of which is fixed a cap 15. A stud 16 is held in the cap 15 and is pivoted at 17 to a bracket 18 secured to the door 2.

The numeral 19 designates a nut which may be said to be threaded upon the screw rod 6, because the nut has internal projections 20, engaged in spiral grooves 21 formed in the screw rod 6. On one end, the nut 19 is provided with clutch elements 22 adapted to cooperate with clutch elements 23 on a clutch member 24.

The clutch member 24 is mounted for swinging movement, and is held against rotation. To this end, the clutch member 24 has a flange 25 attached by screwing elements 26 to an outer sleeve 27 disposed within the holder 14. Inside of the sleeve 27 is located an inner sleeve 28 which has a base 29 of considerable thickness, this base, and the tubular clutch member 24, forming bearings in which the screw rod 6 is mounted for rotation. A retaining device 30, such as a screw, connects the holder 14 with the outer sleeve 27 and with the inner sleeve 28, and a retaining device 31 is engaged with the inner sleeve 28 and passes into the base 29 of the inner sleeve 28. Thus the sleeves 27 and 28 are secured to the holder 14, the clutch member 24 is held against rotation, and the said clutch member is mounted for swinging movement on the bracket 18, along with the holder 14.

On the end of the screw rod 6 there is a ball 32 that turns in a socket 33 mounted to slide in the holder 14. The numeral 34 marks a retractile spring connected at one end, as shown at 35, to the holder 14, and connected at its opposite end, as shown at 36, to the socket 33.

Suppose that the door 2 is closed, parts being in the solid line position of Figure 2, and in the position shown in Figure 5. When the door 2 is opened, the door exerts a pull on the

holder 14 and draws the clutch 24 out of engagement with the clutch elements 22 of the nut 19, the parts then being in the position shown in Figure 4. The screw rod 6 slides freely through the clutch member 24, and the nut 19 turns with the screw rod 6. Although the holder 14 at this time is moved toward the top of Figure 4, the nut 19 is not carried toward the top of Figure 4 to bring the clutch elements 22 and 23 into engagement. This is so because the screw rod 6 does not move lengthwise when the holder 14 moves toward the top of Figure 4, and the projections 20 on the nut 19 (Figure 6) cooperate with the spiral grooves 21 on the screw rod 6 to hold the nut 19 back in the position of Figure 4 in engagement with the base 29. The tubular holder 14 has free longitudinal sliding movement with respect to the screw rod 6, whilst the door is being opened, and during this time, the spring 34 is put under tension.

Suppose that the door is open in the dash line position of Figure 2, that the nut 19 and the clutch 24 are in the position shown in Figure 4, and that the operator lets go of the door. Then the spring 34 reacts and closes the door, and the holder 14 is moved longitudinally a little from the position of Figure 4 to the position of Figure 5 to bring the clutch elements 23 of the member 24, and the clutch elements 22 of the nut 19 into engagement. In this way, the nut 19 (in the position shown in Figure 5) is held against rotation, and the screw rod 6 can slide longitudinally through the nut 19 with a right-line sliding movement, because the projections 20 on the nut have to ride in the spiral grooves 21 of the screw rod 6. The screw rod 6, therefore, is caused to turn with considerable friction, the ball 32 rotating in the socket 33, and the ball 5 rotating in the bracket 4, the closing movement of the door 2 being checked accordingly.

By the time that the door 2 has been swung almost to a closed position, the brake drum 7 of the screw rod 6 comes into contact with the foot 9 of the brake arm 9 of the bracket 4. The rotation of the screw rod 6, therefore, becomes more difficult, and the door gets a final check just before it closes. The operator can advance the screw 12 to shift the brake arm 9, and to regulate the force with which the foot 8 bears on the brake arm 7.

Having thus described the invention, what is claimed is:

1. In a check for swinging doors, cooperating members comprising a holder and a screw, means for mounting said cooperating members for swinging movement and for holding one of them against rotation, and a free nut threaded on the screw and having threaded movement with respect to one of said cooperating members longitudinally of

the screw, said cooperating members having relative right line movement in one direction to bring the nut into end engagement with one of said cooperating members for rotation therewith and for threaded movement along the screw when the door is opened, said cooperating members having relative right line movement in an opposite direction, when the door is closed, to effect an end spacing of the nut and that one of the said cooperating members with which the nut is brought into engagement as aforesaid. 70

2. In a check for swinging doors, a holder, means for mounting the holder for swinging movement but against rotation, a clutch secured to the holder, a screw slidable in the clutch, means for mounting the screw for swinging movement, and a free nut threaded on the screw and provided with a clutch, the holder and the screw having relative longitudinal movement in one direction to space the clutches when the door is opened, and having relative longitudinal movement in an opposite direction to bring the clutches together and to thread the nut along the screw 90 when the door is closed. 80

In testimony that I claim the foregoing as my own, I have hereto affixed my signature.
